Floyd F. Schlitt, 331 Cornell Ave., Elyria, Ohio

Filed Aug. 27, 1957, Ser. No. 680,604

9 Claims. (Cl. 158—113)

This invention relates to conversion units for modifying domestic furnaces for use with gaseous and vaporous fuels and, more particularly, to a new and improved fuel burner.

An object of the invention is to provide a conversion unit for domestic furnaces which is simple and efficient and yet sufficiently compact to be installed in existing furnaces.

Another object of the invention is to provide a compact furnace conversion unit of relatively high efficiency under all conditions of operation.

Still another object of the invention is to provide an improved gaseous and vaporous fuel burner which incorporates an efficient means for secondary air control.

A further object of the invention is to provide an improved gaseous and vaporous fuel burner in which a burner utilizes a pilot burner in conjunction with a secondary air control.

A still further object of the invention is to provide an improved combustion chamber for burners for space heaters.

An additional object is to prevent flame roll out over the full range of burner operating capacity.

Another object is to eliminate the necessity for removing the burner spud fitting or disconnecting the spud from the main gas supply line when the burner is to be removed from or introduced into its casing.

One method of overcoming the limiting conditions which occur in the operation of gaseous fuel burners involves the use of secondary air which is added to the flame to complete the burning of the initial combustion products of the flame. The method is highly efficient but suffers certain disadvantages when used in small burner units due to the complexity of the apparatus required to provide an accurate control of the amount of secondary air.

The present invention involves the use of a burner structure in which the flow of secondary air is along a path concentric with, but separate from the flow of the primary air-gas mixture of the burner element proper. The combustible mixture formed at the burner nozzle is directed through an opening in a burner casing which surrounds the burner element and so that the flame extends vertically through the opening in the casing. A movable baffle surrounds the nozzle and is adapted to be moved toward and away from the casing so as to control the quantity of air which flows from the interior of the casing into the flame opening. The position of the baffle may thus be adjusted for most efficient combustion of the fuel gases or vapors.

In the particular embodiment of the invention disclosed herein, the novel burner is incorporated in a gas conversion unit for solid fuel furnaces and has associated therewith a novel combustion chamber for imparting the heat generated by the flame to the heat exchange elements of the furnace proper. The flame deflector is formed of refractory material and utilizes a novel construction wherein the flame passes along a path between two con-

2

centric members. The arrangement is such that the members may be constructed of refractory materials, while maintaining a simple and compact construction.

It is an important feature of the conversion unit of the invention that the burner element may be readily removed from the conversion unit after installation for servicing of the burner element.

In the course of making this invention I made several entirely unexpected and unpredictable discoveries which have proven to be quite valuable and important. In particular, I found that by providing an opening between the combustion chamber shell and the top of the casing of a conversion burner unit a very substantial improvement in the operating characteristics of the assembly can be consistently obtained. By making this space annular as by providing several spaced supports for the combustion chamber shell and by maintaining the axial dimension of this annular space within certain limits, results hitherto unobtainable can be secured in regular production models of the burner assemblies of this invention.

I further found that the tendency for roll out of flame, which is particularly marked in conversion units of this type in high capacity burner operation, can be eliminated by providing a form of baffle at a particular location with respect to the burner nozzle in the units of this invention.

These and other discoveries that I made and the new features that I have incorporated in the present assemblies are embodied or incorporated in the assemblies and apparatus described in detail below and illustrated in the drawings accompanying and forming a part of this specification in which:

Fig. 1 shows a partial section of the conversion unit of the invention as installed in a domestic furnace;

Fig. 2 is a plan view taken along the lines 2—2 in Fig. 1;

Fig. 3 is an enlarged view showing particularly the secondary air regulator and the combustion chamber of the invention;

Fig. 4 is a horizontal section of the combustion chamber taken along the lines 4—4 in Fig. 1;

Fig. 5 is a plan view of an alternative embodiment of the secondary air regulator of the invention;

Fig. 6 is a view showing an alternate form of the central pier support for the combustion chamber;

Fig. 7 shows an alternate form of the upper deflecting member of the combustion chamber;

Fig. 8 is an elevational, longitudinal, sectional view of a conversion burner assembly embodying this invention in a preferred form;

Fig. 9 is a top plan of the assembly of Fig. 8 with upper portions removed to show the arrangement of the main burner and its spud fitting in the burner casing;

Fig. 10 is a longitudinal, sectional view of the secondary air regulating device of the assembly of Fig. 8;

Fig. 11 is a top plan view of the regulator of Fig. 10;

Fig. 12 is an end view of the Fig. 10 regulator taken on line 12—12;

Fig. 13 is a vertical, sectional view of the burner nozzle of the assembly of Fig. 8 showing fragmentarily the nozzle disc and means securing the disc to the nozzle;

Fig. 14 is a top plan view of the combustion chamber spacer plate of the Fig. 8 assembly; and,

Fig. 15 is a vertical, sectional view of the plate of Fig. 14 taken on line 15—15.

Referring now to Fig. 1, the conversion unit 10 of the invention is shown as installed in the ash box 11 of an ordinary domestic furnace 12. The walls of the fire pot 13 serve as a heat exchange medium for transmitting heat generated by the conversion unit 10 to a stream of air which is admitted to the furnace through a cold air inlet 14 as is customary in the art.

The conversion unit 10 comprises a burner unit 15 for producing a combustible mixture of fuel and air and for supplying a suitable amount of secondary air to the flame generated by combustion of the mixture. A combustion chamber 16 confines the flame of the burner unit in such a way as to provide optimum combustion conditions for the burning air-gas mixture. The combustion chamber also serves to deflect the products of combustion so as to facilitate the transmission of heat to the walls of the fire pot 13. The burner unit 15 is of such a size that it may be inserted into the ash box 11 through the front door thereof while the combustion chamber 16 may be separately inserted and positioned atop the burner unit.

The burner unit 15 comprises a sheet metal outer casing 17 and a burner, including a burner element 18 mounted within the casing, and a secondary air regulator 19. The burner element 18 is of well known construction and includes a gas inlet 20, an air inlet 21 and a needle valve 22 for regulating the primary gas-air mixture. A burner nozzle 23, mounted at the end of the burner element 18, may be of the same type as is disclosed in my copending application, Serial No. 254,067, filed October 31, 1951, now United States Patent No. 2,757,723.

A pilot burner 24 is mounted upon the burner element 18 and is supported adjacent an ignition slot which is formed in the side wall of the burner nozzle 23.

The burner element 18 is supported from the bottom wall 25 of the casing 17 by a forward leg 26 and a rear leg 27. Flange portions 28 and 29 rest upon the bottom wall and provide lateral support for the burner element. The burner element is held in place by stops 30 so that the burner element may be removed from the burner casing through the opening 31 for servicing. It is to be specifically noted that because of the organization of the burner and pilot burner, it is particularly advantageous in that the position of the pilot burner is fixed and need not be disturbed when the burner element is removed for service. As a result, the usual dangers of explosion due to malpositioning of the pilot burner after the burner proper or the pilot burner is serviced are obviated.

The nozzle 23 is disposed below and aligned with an opening 32 in the upper wall of the casing 17. The combustible mixture from the nozzle 23 is directed through the opening 32 and combustion takes place in the region immediately above the nozzle.

The casing 17 serves as an enclosure for determining flow of secondary air from the open end 31 of the casing to the opening 32. The air flows along the casing and concentrically about the body of the burner element 18 and the burner nozzle 23 so that there is a uniform flow of secondary air into the space above the nozzle from all sides of the nozzle. The rate at which this secondary air flows into the opening and is supplied to the burning mixture is controlled by a secondary air regulator including a baffle 33. The baffle 33 surrounds the nozzle 23 and cooperates with the upper wall 37 of the burner casing to restrict the movement of the secondary air.

The baffle 33 is of generally annular shape and comprises a horizontal portion 34 which has an opening 35 which is slightly larger than the outside of the nozzle 23. A vertical portion 36 extends upwardly from the portion 34 around the outer periphery thereof and abuts the inner surface of the top wall 37 of the casing 17 when the horizontal portion 34 is adjacent the upper extremity of the nozzle 23. The baffle 33 is supported by an arm 38 which is supported from the burner element 18 by a pivot member 39. The baffle 33 is fixed in position with respect to the nozzle 23 by means of a set screw 40 and a second member 41. The members 39 and 41 form an integral part of the burner element so that the entire assembly may be removed from the burner casing 17 for servicing.

The combustion chamber 16 comprises an outer por-

tion 50 and a central portion or pier 51 which is disposed within the outer portion 50 so as to form a generally coaxial opening 52 between the two portions. The outer portion 50 comprises a sheet metal casing 53 which may be attached to the upper wall 37 of the casing by any suitable means and a lining comprising a flat annular member 54 and a cylindrical member 55. The lining members 54 and 55 are of refractory material and are supported by the top wall 37 of the burner casing.

The pier 51 is also formed of refractory material and comprises a lower cup-shaped member 56, a cylindrical central member 57 and an upper deflecting member 58. The pier is supported by a metallic support member 59 which comprises a conical piece 60 having three radially extending legs 61 which engage the upper wall 37 of the burner casing. The cup-shaped pier member 56 has a lower tapered portion 62 which forms a continuation of the side walls of the conical piece 60. As shown in Fig. 4, the pier members are provided with three radially extending fins 63 which maintain the spacing of the pier members from the lining members of the outer portion 50 of the combustion chamber.

In use, the conversion unit is mounted in the ash box 11 of the furnace. The ash box opening is then closed by a sheet metal member so that the only air which reaches the interior of the ash box 11 and fire pot 13 must pass through the burner casing and through the flame opening 32. Positive control of the secondary air supply is thus assured by adjustment of the position of the baffle 33 of the secondary air regulator.

Referring now to Fig. 5, there is shown an alternate embodiment of the secondary air regulator of the invention. The baffle 64 is similar in cross section to the baffle 33 of Fig. 1 but is formed in two semi-annular pieces 65 and 66. The pieces 65 and 66 are supported by arms 67 and 68 and are, in turn, supported by two pivot members 69 and 70 which are secured to the burner casing 17. The pieces 65 and 66 may thus be moved toward and away from each other and from the burner nozzle to control the quantity of secondary air moving into the space above the burner nozzle 23. The ends of the arms are disposed within the burner casing and may be used as handles to adjust the baffle pieces. The top part of the vertical wall portion of the baffle members is, of course, separated from the top wall of the burner casing by a small amount so as to minimize the flow of secondary air between the baffle and the casing while permitting horizontal adjustment of the baffle pieces.

Referring now to Fig. 6, the alternate embodiment of the combustion chamber incorporates a central pier which is supported by a lower pier member 71 rather than by a separate metallic piece as in the embodiment of Fig. 1. The lower pier member 71 has conical lower portion and is supported by a plurality of radially extending fins 72 which rest upon the flat annular member 73 of the outer portion of the chamber. The central pier member 74 is provided with radial projections 75 which maintain the spacing between that member and the cylindrical outer member 76. The combustion chamber members are, of course, formed of refractory material.

Referring now to Fig. 7, there is shown an alternate embodiment of the combustion chamber which is generally similar to the chamber of Fig. 1 in that it incorporates a metallic pier support. The outwardly projecting portion 77 of the upper deflecting member 78 is, however, tapered upwardly to modify the path of the products of combustion as they leave the combustion chamber. The particular form of upper deflecting member adopted will, of course, be dependent upon such factors as the flame rate, exhaust velocity, etc.

The burner assembly illustrated in Figs. 8 and 9 is basically similar to that of Figs. 1 and 2 in that they both incorporate the same certain novel features of this invention. The assembly of Figs. 8 and 9, however, in-

cludes additional features and embodies additional discoveries of mine specifically mentioned above.

This latter assembly thus comprises a sheet metal burner casing 80 which has an opening at one end indicated at 81 which serves as both an access opening and as an air inlet opening for main burner and pilot burner primary and secondary air supply. In the top wall of casing 80 remote from end 81 a flame opening 84 is provided. A straight rail 85 and an angular rail 86 are spot welded to the bottom wall of casing 80 and located with respect to each other and to flame opening 84 so as to insure alignment of the main burner nozzle with the flame opening when the burner is installed in the casing.

Main burner 87 as shown in Figs. 8 and 9 is positioned with its axis at a small angle to the longitudinal axis of the casing and with its leg 88 wedged between the rails 85 and 86 near their inner ends and its leg 89 abutting rail 85 near its outer end. Burner spud fitting 90 is disposed coaxially of the main burner and adjacent to the inlet end thereof in accordance with standard practice and requirements. This spud fitting is semi-permanently fixed to the bottom wall of the housing. In other words, according to standard requirements is not readily removed from its original position. The main gas supply line 92 is connected to the spud fitting and by virtue of the easy removability of burner 87 without disturbing the spud or disconnecting the main gas supply line, the entire gas supply system may be left undisturbed when the burner is to be replaced or repaired. Rails 85 and 86 as indicated in outline on Figure 8 permit swinging of the inlet end of burner 87 away from spud 90 in order to clear the burner for withdrawal from engagement with the rails and through opening 81 between the spud fitting and the opposed side wall of casing 80.

Pilot burner 94 is suitably the same as pilot burner 24 of Fig. 1 and thus is located with respect to main burner nozzle 95 so as to serve the burner after the manner described in my United States Patent No. 2,757,723, granted August 7, 1956. Details of construction of my patented nozzle 95 are illustrated in Fig. 13 where nozzle disc 97 is secured in position on top of the nozzle by means of self tapping screws 98.

Control over flow of secondary air for both the main burner and the pilot burner is afforded by the apparatus shown in Figs. 10 and 11. This apparatus, which is also shown as part of the assembly of Fig. 8 in closed position and in outline in open position, includes a cup-shaped body or secondary air cup 100 having an enlarged central opening 101 to receive the nozzle end of the main burner and the pilot burner. Cup or body 100 is provided with a rigid handle or operating lever 102 supported by a pivotal connection to a supporting bracket so that gravity will tend to maintain the cup in wide open position. The pivoted connection is made by means of pin 104 disposed through registered openings 105 in lever 102 and through an opening in a supporting bracket 107 for the secondary air control apparatus mounted on burner 87.

Lever 102 is made up of a channel 108 which is welded to the bottom of cup 100, a channel 109 in the sides of which openings 105 are provided and a pair of metal fastening straps 110 and 111 which are welded to the adjacent ends of the channels 108 and 109, holding them rigidly together with the channels opposed to each other as shown to best advantage in Fig. 12. A nut 114 is welded to the web of channel 109 near its free end in register with an opening in the channel web to receive a screw 115 shown in Fig. 8. Screw 115 bears at all times against a flange portion of bracket 107 to maintain body 100 in predetermined position with respect to burner 87 and flame opening 84. Thus by merely turning screw 115, the secondary air gap may be opened or closed or cup 100 can be set at any intermediate position, lever 102 moving around its pivot in response to adjustments of screw 115 as indicated in Fig. 8.

Combustion chamber 120 is maintained on and sup-

ported by burner casing 80 and consists of two basic elements, namely a hollow refractory body 121 and a spacer plate 122 to support body 121 in vertical spaced relation to casing 80 to provide an annular opening 124 for gas flow between body 121 and casing 80 to relieve combustion chamber pressure during main burner ignition. In addition, as shown in Fig. 8, the combustion chamber will normally include a center pier 125 in body 121 and means including three legs 126 (two shown in Fig. 8) for supporting the pier in position above flame opening 84.

Refractory body 121 may suitably be of cylindrical or polygonal form but it must be open at its two ends and in accordance with this invention it must be disposed above casing 80 to provide annular space 124. In addition the refractory body should be composed of material suitable for service over long periods of use under the conditions of maximum capacity of the burner and the furnace in which this assembly is installed. It is also desirable that refractory body 121 be centered with respect to the burner nozzle and flame opening 84 and that it be substantially uniformly spaced radially from center pier 125.

Spacer plate 122 comprises a thin metal sheet or bed plate 123 which has a central opening 127 closely approximating in size and shape flame opening 84 in casing 80. Bed plate 123 may be secured to casing 80 by means of tack or spot welds at the four corners of the plate in order to maintain these parts in assembled relation during installation and use. Six short rails 130 are welded to the top of the plate and located at uniform intervals around the circumference of the central opening 127 with their inner ends adjacent to the inner periphery of the bed plate. These rails, as shown in Fig. 35, 15, are angle irons which have been formed with upstanding tabs 131 at their ends remote from opening 127 so that they provide lateral abutments to guide and hold refractory body 121 in centered position with respect to flame opening 84 and the nozzle of burner 87. The upper edges of these rails or irons extending inwardly from tab 131 engage the lower end or edge portion of refractory body 121 and support the body in upright position and spaced relation to casing 80. The height of these rails above bed plate 123, except for the tab portions 131, is preferably carefully fixed in accordance with this invention to provide the optimum dimensions of gap 124. I have found, for example, that in gas conversion burners of this invention designed for the ordinary heating furnace using a burner of maximum capacity in the range of 400,000 B.t.u. per hour maximum gas input rating, gap 124 should be about 1½ inches high (axial dimension).

Three rails 135 which appear U-shaped in plan view are welded to plate 123 at locations 120 degrees apart around the inner periphery of the bed plate. These rails are modified angle irons, the flange portions of which are disposed against and welded to the upper face of the bed plate 123 while the inner ends are situated adjacent to opening 127. These rails in cooperation with the bed plate thus provide pockets in which to receive the lower ends of legs 126, this relationship being illustrated in Fig. 8.

Pier 125 comprises a conical, metallic, support member 138 to which the upper ends of legs 126 are welded; a cylindrical, central, refractory member 139 which rests on the inverted base of conical member 138 and an upper refractory deflecting member 140 which rests on the upper end of cylindrical member 139. The diameter of cylindrical member 139 is substantially the same as the diameter of the base of support member 138, while the diameter of deflecting member 140 is substantially greater, approximating the inside diameter of body 121. This pier assembly is supported in position in the combustion chamber with the apex of member 138 above the central opening of burner nozzle 95.

With the parts of the combustion chamber thus located with respect to each other the best flame flow patterns and operating characteristics of the entire conversion burner apparatus will be obtainable. Flame entering the combustion chamber through flame opening 84 will flow substantially uniformly through the combustion chamber and produce maximum heating effects. At the same time the burner and burner nozzle and other parts within casing 80 will not be subject to high temperatures in the range of combustion chamber temperatures in operation or exposed to radiant heat in large amounts as is typical in prior conventional burner assemblies. This combustion chamber in other words will operate more efficiently and at a higher temperature and higher heat level on a given gas input, and the burner components in casing 80 will operate at substantially lower temperature levels than the corresponding elements of prior art devices of this general type.

I have found that under certain circumstances nozzle disc 97 will function not only to prevent flame roll out as it cooperates with gap 124, but also this disc will control the secondary air supply in cooperation with adjacent portions of casing 80. Disc 97 in the illustrated embodiments is not adjustable in position relative to the burner casing but its initial position may be established in accordance with predetermined secondary air requirements of normal operation of the main and pilot burners so that no additional secondary air control or regulation means such as cup 100 will be required to make the apparatus operate properly and efficiently.

While the novel burners and combustion chambers have been particularly illustrated and described with reference to conversion units for a warm air heating system, it is nevertheless intended that the apparatus be equally useful in connection with hot water and steam boiler systems either as conversion units or in original installations.

This is a continuation-in-part of my copending application Serial No. 389,274, filed October 30, 1953, and entitled Conversion Burner.

Having thus described this invention in such full, clear, concise and exact terms as to enable any person skilled in the art to which it pertains to make and use the same, and having set forth the best mode contemplated of carrying out this invention, I state that the subject matter which I regard as being my invention is particularly pointed out and distinctly claimed in what is claimed, it being understood that equivalents or modifications of, or substitutions for parts of the above specifically described embodiments of this invention may be made without departing from the scope of the invention as set forth in what is claimed.

What is claimed is:

1. A transportable conversion burner unit comprising a casing to be inserted in the ash pit of a domestic furnace and having top, bottom, end and side walls, the casing defining an air inlet between said top and bottom walls and a flame opening in the top wall remote from said air inlet, a burner in the casing, the burner including a nozzle, the burner being fixed to the bottom wall thereof with its fuel inlet at said air inlet and the nozzle aligned with said flame opening and spaced below said top wall, and means for regulating the air flow through said flame opening including a baffle in the casing around said nozzle and movable toward and away from said top wall, and means in the casing pivotally supported by said burner and carrying said baffle.

2. The combination of elements set forth in claim 1 in which a pilot burner is mounted on said burner to receive primary air at a point below the baffle and secondary air at a point above the baffle and in which said baffle is provided with a recess to receive said pilot burner.

3. The combination of elements set forth in claim 1 in which said casing is provided with a combustion chamber on the top wall thereof around said flame opening.

4. The combination of elements set forth in claim 1 in which said casing is provided with a combustion chamber including a metal shell attached to the top wall of the casing around said flame opening, and a refractory liner within said shell to provide a combustion space coaxial with said burner.

5. A burner unit comprising a burner casing having top and bottom walls, an inlet opening at one end thereof and a flame opening in the top wall of the casing at the 10 remaining end thereof, a burner comprising a burner element having an inlet end thereof at the inlet end of the casing and a nozzle at the remaining end of the burner element and disposed below the top wall of the casing and aligned with the flame opening, 15 means secured to the inside of the burner casing for removably mounting the said burner in the burner casing, ignition means comprising a pilot burner mounted adjacent the nozzle and supported by the burner, and a secondary air regulator comprising an annular baffle surrounding the nozzle and carried by an arm and a pivot for the arm mounted upon the burner, to permit vertical movement of the baffle relative to the nozzle and the top wall of the casing, whereby the said burner, the said pilot burner and the said air regulator are fixed with respect to each other and constitute a unitary apparatus which may be removed from the burner casing through the inlet end thereof.

6. A gas conversion burner assembly comprising a burner casing having top, bottom, side and end walls, the casing having an air inlet between the top and bottom walls and a flame opening in the top wall remote from the air inlet opening, a burner in the casing, the burner including a nozzle having an outlet opening aligned with and below the flame opening, and a combustion chamber above the casing including a hollow refractory body open at its ends and means for supporting said body above the casing top wall in vertical spaced relation to the casing to provide an annular opening to relieve combustion chamber pressure during main burner ignition.

7. In a burner unit including a casing having top, bottom, end and side walls, a flame opening in the top wall, a burner in the casing with its nozzle aligned with the casing flame opening, and means for regulating secondary air flow through the casing flame opening including a cup-shaped body within the casing and having an enlarged central opening to receive the burner and a lever for moving that body toward and away from the casing top wall, the combination of a disc carried by the burner and having a diameter greater than said cup shaped body central opening, said disc cooperating with the cup-shaped body to prevent flame roll-out when the body is in open position and said disc being in substantially annular abutment with the cup shaped body to prevent flow of secondary air around the burner nozzle when the body is in closed position.

8. A transportable conversion burner unit comprising a casing to be inserted in the ash pit of a domestic furnace and having top, bottom, end and side walls, the casing defining an air inlet between said top and bottom walls and a flame opening in the top wall remote from said air inlet, a burner in the casing, the burner including a nozzle, the burner being removably fixed to the bottom wall thereof with the nozzle aligned with said flame opening and spaced below said top wall, a burner spud fitting in the casing and fixed to the bottom wall thereof, and burner guide means comprising rails secured to the casing bottom wall and disposed relative to the spud fitting and the flame opening to guide the burner in travel relative to the stationary spud fitting during burner removal from and introduction into the casing whereby burner replacement and repairs can be accomplished without disconnecting the spud fitting from its main gas supply line.

9. In a burner unit including a casing having a flame opening in its top wall and a burner in the casing with

its nozzle aligned with the casing flame opening, the combination of a cup shaped body having an opening in the bottom thereof, the body being disposed around and spaced from a portion of the burner with the burner projecting through said opening, a disc connected to the top of the burner in annular abutment therewith and cooperating with the cup shaped body to prevent flame roll back and to regulate the supply of secondary air to the burner, said disc having a diameter greater than the diameter of the opening in the bottom of said cup shaped body, and means interposed between the cup shaped body and the casing to adjustably move the cup shaped body relative to said casing and relative to said burner and to selectively move said cup shaped body into substantial annular abutment with said disc with the disc disposed within the cup. 15
